(57) **CLAIM**

The ornamental design for a portable electric circular saw, as shown and described.

DESCRIPTION

FIG. 1 is a photograph corresponding to a front elevational view of a first embodiment of the portable electric circular saw;

FIG. 2 is a photograph corresponding to a rear elevational view thereof;

FIG. 3 is a photograph corresponding to a left side view thereof;

FIG. 4 is a photograph corresponding to a right side view thereof;

FIG. 5 is a photograph corresponding to a top plan view thereof; and

FIG. 6 is a photograph corresponding to a bottom plan view thereof.

FIG. 7 is a photograph corresponding to a front perspective view thereof;

FIG. 8 is a photograph corresponding to a front elevational view of a second embodiment of the portable electric circular saw;

FIG. 9 is a photograph corresponding to a rear elevational view thereof;

FIG. 10 is a photograph corresponding to a left side view thereof;

FIG. 11 is a photograph corresponding to a right side view thereof;

FIG. 12 is a photograph corresponding to a top plan view thereof; and

FIG. 13 is a photograph corresponding to a bottom plan view thereof; and,

FIG. 14 is a photograph corresponding to a front perspective view thereof.
